Atty's.

UNITED STATES PATENT OFFICE.

ANGELO VILLANI, OF WILMINGTON, DELAWARE.

SEWING-NEEDLE.

1,345,422.

Specification of Letters Patent.

Patented July 6, 1920.

Application filed October 7, 1919. Serial No. 329,012.

To all whom it may concern:

Be it known that I, ANGELO VILLANI, a citizen of the United States, and resident of Wilmington, Delaware, have invented certain new and useful Improvements in Sewing-Needles, of which the following is a specification.

My present invention relates to an improved hand device for overseaming, darning and analogous operations and aims to provide a simple, economical and efficient device which will greatly facilitate the work of the house-wife and the invention includes the novel features of construction and arrangement and combination of parts hereinafter described and defined by the appended claims.

An embodiment of my invention is illustrated in the accompanying drawing in which—

Figure 1 is a side elevation of a device embodying my invention and

Figs. 2 to 6 are detail views.

Referring by reference characters to this drawing the numeral 1 designates the needle which may be of any suitable length and thickness and which is pointed in the usual manner to enable it to penetrate the material to be sewed.

One side of the needle at a suitable distance back from the point is provided with an elongated recess 1^a in the center of which is pivoted a latch member 2 which is slightly longer than one half the length of the recess.

The forward end of the recess is shaped to form a hook, indicated at 1^b to catch the thread and draw it in loop form through the fabric as hereinafter more fully described, and in one position the free end of the latch is designed to rest against the upper edge of the hooked portion 1^b and in the other extreme position to rest against the shoulder 1^c, in each position projecting slightly above the surface of the needle so as to be caught and swung by the fabric when the movement of the needle is reversed.

Associated with the needle is a combined handle and spool holder, the handle comprising a frame member 3 of open loop form, to one arm 3^a of which the rear end of the needle is rigidly secured. The other arm 3^b which is substantially parallel to the opposite side, is provided at its extremity with a boss 3^c which engages an eye 4^a of a spool holder supporting arm 4.

The side of the frame opposite the arm 3^b is provided with an aperture 3^x to receive the end of the spool holder sleeve 5, said sleeve being closed at its outer end, and being provided at the opposite end with a flange 5^a designed to engage the spool end. The frame carries a disk 6 adapted to engage the opposite end of the spool which is clamped between this disk and the flange 5^a with sufficient force to give the desired frictional resistance to the rotation of the spool which is placed on the sleeve 5.

Within the sleeve 5 is placed a spring 7 which bears at one end against the closed end of the sleeve and at the opposite end against the end of the arm 4.

The spring, therefore, tends to force the sleeve and flange 5^a toward the disk 6, while to remove and replace the spool it is only necessary to press the flange 5^a backward against the tension of the spring until the end of the sleeve is clear of the opening in the frame, when the arm 4 may be swung around on its pivot on boss 3^c and the spool removed and replaced.

From the foregoing it is though the manner of using my device will be obvious, but it may be briefly stated as follows:

For overseaming, for example, the needle would be pushed through the juxtaposed edges of the fabric which would cause the free end of the latch to be engaged by the fabric and swung back against the shoulder 1^c, it being understood that the needle is pushed through the fabric until the latter has passed the end of the latch in its backward position.

The thread 8 is then drawn from the spool 9 and laid in the hook 1^b of the needle which is then drawn through the fabric to form a loop.

The needle is then again inserted through the fabric at a suitable distance from the previous point of penetration, the latch again swinging backwardly, and the thread is again laid in the hook which is again withdrawn and so an *ad infinitum*.

Having thus described my invention, what I claim is:

1. In combination, a needle, a handle therefor having a post, an arm having an end pivotally supported by the post, a spool support carried by the arm, and means for holding the arm against swinging.

2. In combination, a needle, a handle therefor having two substantially parallel

105

110

side members, an arm pivotally connected to one of said members, a tubular spool holder removably carried by said arm and having a spool engaging flange, the other handle member having a part to be engaged by said spool holder, and a spring acting on said spool holder.

3. In combination, a needle, a handle therefor having two substantially parallel side members, an arm pivotally connected to

one of said members, a tubular spool-holder removably carried by said arm, said tubular spool-holder being closed at one end and having a spool engaging flange at the other, a spring within said spool holder between 15 said closed end and the end of the arm, the other handle member having a recess to receive the end of said spool-holder.

In testimony whereof I affix my signature
ANGELO VILLANI.
